PULVERIZER

Harry Raymond Collins, Allentown, Pa., assignor
to The Babcock & Wilcox Company, Bayonne,
N. J., a corporation of New Jersey

Application November 4, 1931, Serial No. 573,021

24 Claims. (Cl. 83—45)

This invention aims to provide an improved grinding or pulverizing machine of the type shown in my Patent No. 1,386,093 dated August 2, 1921, wherein a series of crushing balls are revolved about a central axis upon an annular raceway.

Several objects and advantages are contemplated, and these as likewise the invention itself will be best understood by description with reference to the attached drawings illustrating one practicable embodiment, along with several modifications which may be more adaptable to different working conditions.

In said drawings:

Fig. 1 is a side view of the illustrative embodiment, showing one-half in vertical section and the other half in elevation;

Fig. 2 is a plan view of the same showing one-half open with upper parts removed and the other half closed;

Fig. 3 is a plan view of the material feed mechanism shown sectionally in Fig. 1;

Fig. 4 is a section on the line 4—4 of Fig. 1;

Fig. 5 is an end view on the sectional line 5—5 of Fig. 1;

Fig. 6 is a partial sectional view of a modification embodying a single series of grinding balls;

Fig. 7 is a similar view of another modification having three series of balls;

Fig. 8 is a like view of a further modification having four series of balls; and

Fig. 9 is a fragmentary view diagrammatically representing the chilling of the ball-raceway surfaces.

The exemplary machine or mill being essentially circular in form is mounted advantageously on a circular concrete foundation 10 having a ring-plate 11 grouted in its top to assure a firm, even and level rest.

Its base or body part is provided in this instance by an annular bowl-like casting 12 fastened down upon said plate by bolts (not shown) anchored in the foundation. This casting is formed with a radial clean-out opening at one side closely normally by a door 13, affording ready means of removing such foreign material or matter as may find its way into the machine, while a skeleton sliding plug 14 serves to prevent accumulation of pulverized material settling in said clean-out opening. At the opposite side, an opening 15 adapted to connection with a conduit is provided for a purpose which will later appear.

Secured as by bolting to the underside of said

casting is a housing member 16 having a central hub-like extension 17 on its lower side providing journal bearing for a shaft stepped upright therein. Supported vertically therewithin is a rotary main shaft 18 having intermediate 5 or opposite end journalment in bearing 19 provided centrally of the aforesaid casting as by separate casting bolted thereto as shown. These bearings of course have liners or bushings 20 adapted to lubrication as common to machine 10 shaft assemblies.

Said shaft is adjustably stepped in this instance upon a pintle bearing 21 having a wearing disk 22 thereunder with bottom-washer 23 resting against a screw 24, the latter being turnable 15 in adjusting nut 25 carried by a cap 26 which is fastened to said extension of the housing and in turn houses these parts as a step support. Said screw shown projecting from this cap is squared for locking to adjusted position by nut 20 27, while packing to prevent escape of bearing lubricant may be held by a gland nut 28 bolted with the former to the cap end.

The aforesaid shaft carries a pentagonal driving head 29 on its upper end, secured thereto as 25 by key-splining and lock-nut fastening. Its drive means by which high speed rotation may be imparted will be later described.

Supported on the upper end of the aforesaid casting (12) is a grinding ring 30 of annular form having an annular groove fitting over a corresponding ridge 31 of said casting for accurate centering thereon. These two parts are rigidly connected together as by bolts 32 passed through the ring. This ring is shown 30 formed with oppositely inclined faces 33 and 34 at opposite sides of its inner periphery, having raised (see Fig. 9) and chill-hardened surfaces of glassy smoothness and hardness represented by cross-hatched portions thereof providing annular ball-raceways. Being subjected to heavy wear and pressures, the ring is preferably cast from a mixture of iron having a low content of sulphur, silicon and phosphorus to avoid weakening, with manganese from 0.4 to 0.6 percent 45 to give depth to the chilled faces, followed by mottled iron and in turn followed by gray iron to give strength. The depth of the chilling over an arcuate area in straight and angular lines to the chill as represented in aforesaid Fig. 9 is such 50 as to present a substantially wide and hard surface, susceptible of grinding to a smooth, true annulus for the balls so as to minimize ball jumping, vibration, noise and wear.

Between the raceway surfaces of said ring, an 55

inner peripheral extension is provided as by plate 35 machined or otherwise fixed thereto and desirably having a marginal bead around its upper edge. This extension serves as a shelf for supporting the balls when assembling the mill, and as a drop-ledge for material during operation of the mill.

On the upper (33) of the raceway surfaces, an annular series of balls 36 is revoluble. These 10 balls are of forged steel, heat-treated and hardened. In this instance there are ten of twelve-inch diameter to the series, weighing approximately 256 pounds each. Balls of such size and weight will nip and crunch quite large granular 15 or lumpy material without the slightest difficulty.

On the lower (34) of said raceway surfaces is revoluble another annular series of balls 37 the same as the former except as to size and number, there being in this instance twelve of only ten-inch diameter to the series, weighing approximately 148 pounds each. These of course work on finer material and crush to the pulverizing point.

25 The upper series of balls is held down on the upper raceway of the grinding ring by a pressure plate or disk 38 having two faces 39 at obtuse angular relation of approximately 120 degrees apart, or with one at 15 degrees from the horizontal and the other at 15 degrees from the vertical, providing annular bearing raceways of different diameters concentric with and opposite to said raceway of the ring. These faces have raised and chill-hardened surfaces represented by the cross-hatched portions thereof, similar to and for the same purpose as the raceways of said ring. The plate or disk is also cast preferably from the same metal as the grinding ring to assure like strength, hardness and wear qualities. It rests upon the 40 balls with its said surfaces contacting their upper sides equi-distant from a diametrical plane perpendicular to the raceway of the ring and so holds them in a three-point balance as illustrated in Fig. 1 by the dotted lines through the balls. 45 In this position it engages centrally over or with the driving head (29) on the rotary shaft so as to be driven therewith. It is adapted to yielding pressure action on the balls, in this instance by an annular series of bolts 40 compressing springs 50 41 thereagainst within wells 42 therein formed for the purpose.

The lower series of balls is held up on the lower raceway of the grinding ring by another pressure plate or disk 43, having faces 44 corresponding 55 to those of the first, and of the same material of which it is formed. This latter plate bears under the balls with its said surfaces contacting their lower sides equidistantly from a diametrical plane perpendicular to the raceway of the 60 ring in the same way as the former and similarly engages over or with the driving head on the rotary shaft for driving therewith. This plate is likewise adapted to yielding pressure action on the balls, in this instance by passing the aforementioned bolts 40 therethrough so that the two plates will be drawn together and serve at the 65 same time to support the lower one.

The two plates thus drawn together tend to squeeze the balls of both series in firm traction 70 upon their raceways with co-ordinated pressures. Being jointly or cooperatively rotated by the driving head with drive of the rotary shaft, they impart revolution to their respective ball series according to the speed of said shaft and cause the 75 balls to turn as well as roll on their raceways.

the upper series of balls of course being revolved a lesser number of times per cycle than the lower series because of the difference in size. Assuming the upper series travels an annulus of 32 inch diameter and the lower series travels an annulus of 34.5 inch diameter and the machine is driven at the rate of 100 revolutions per minute, the balls of the upper series (having a total weight of approximately 2560 pounds) will be revolved 266 times per minute, while the balls of the lower 10 series (having a total weight of approximately 1776 pounds) will be revolved 345 times per minute.

15 In this illustrative machine, the rotary shaft is driven by a ring-gear 45 carried by spider 46 keyed and locked thereon within the aforementioned housing (16). This gear meshes with pinion 47 keyed on the end of a drive shaft 48 projected horizontally into said housing.

The last-named shaft is shown extending 20 through a combined oil-pump and reservoir casing 49 connected to an open side of the housing formed with bottom slope theretoward for drain into its lower reservoir space through communicating passage 50. Said shaft has support in 25 bearings 51 and 52, the former being advantageously formed as part of said casing and the latter being fixed on a standard 10^x formed desirably as part of the concrete foundation. Each of these bearings of course has the usual 30 liners or bushings 53 with channels for lubrication. On its other end the shaft carries a pulley or head 54 for either belt or flexible-joint connection with a power-drive plant (not shown). It also carries a pulley 55 for driving-belt connection 35 with another part later described. A grooved pulley 56 thereon adjacent the casing provides for belt drive of the oil-pump next described.

Said oil pump in this instance comprises a 40 pair of pumping gears 57 and 58 (see Fig. 5) housed in the wall of the aforementioned casing (49) at the level of its reservoir space and driven by grooved pulley 56 from the first-mentioned such pulley on the driving shaft. These 45 pump gears may be exposed to the oil in the reservoir space of the casing, or draw it in by siphonic action through a lead-in pipe 60, as preferred. An outlet pipe 61 therefrom leads through a flow-gauge 62 to a distributing manifold 63. From this manifold, a pipe 64 leads to the lower and step-bearings of the rotary shaft (18), another pipe 65 leads to the driving shaft bearing (51), a third pipe 66 leads to the teeth of the driving pinion (47) and a 55 fourth pipe 67 leads to the upper bearing (19) of the rotary shaft.

The pumped oil excess or overflow from the aforesaid parts returns to the reservoir space of the casing, which is provided with a filler cap 60 68 for replenishing the supply as necessary, while a valve controlled drain 69 in the bottom of the casing provides for drawing off used oil and sediment. A thrust-collar 70 therewithin on the driving shaft is advantageously splattered with 65 sufficient lubricant by an oil-slinger blade 71 thereon dipping into the supply.

The described grinding elements are encased as by a cylindrical shell 72 shown resting on top of the grinding ring (30) and having a retainer ring 73 bolted thereto with rib-fitting into a centering groove thereof similarly to the latter's mounting on the base casting. This shell has a tapering top 74 connecting with a flue-pipe (not shown) leading to a collecting or storage 75

receiver (also not shown) and provided with an inward neck extension or baffle 75 at its central opening. Around this neck are a series of deflectors 76 arranged in tangential relation thereto (see Figs. 1 and 4). Suspending from around the lower ends of these baffles is an inverted cone-funnel 77 opening above the upper pressure-plate (38). Encircling the lower end of this funnel and also said plate is an inner shell-member 78 secured on the grinding ring concentrically with the outer shell member and providing a trough-space around the grinding elements within the main shell area, as also an annular passage 79 therebehind. On top of said upper pressure-plate, a cover plate 80 having a raised conical center under the funnel and thimbles 81 around the compressor springs shield the same against material dropped through the funnel and allow it to be thrown off against the trough sides. A door 83 in one side of the main shell provides access thereto for cleaning and inspection purposes.

Encircling the lower pressure-plate (43) is another inner shell 84 secured to the bottom 25 of the grinding ring and providing an annular passage 85 therebehind as also a discharge opening 86 below the lower ball level. This inner shell together with the lower pressure-plate in effect forms the bottom of the trough, of which 30 the aforesaid grinding ring forms part of the side.

The aforesaid annular passages 79 and 85 behind the trough wall are opened to each other in this instance by an annular series of communicating passages 30' through the grinding ring behind its raceway surfaces, with the effect of a continuous annular space between the trough and outer shell from the bottom of the machine to above the lower end of the funnel.

40 A continuous air blast through these passages from the bottom toward the top of the machine is maintained during operation of the machine. This air blast is generated by a fan unit 87 having outlet conduit 88 connecting with the aforesaid opening 15 of the casting member (12). This fan unit is preferably driven independently.

The material to be pulverized in the machine is fed through a hopper 89 having spout 90 extending into the inner trough space with a swinging baffle-plate 91 on its end. The material is supplied through a conduit (not shown) connecting with the top of the hopper. It drops onto an arcuate plate 92 over the edges of which 55 it is pushed by a swinging blade 93 in regulated feed. This blade oscillates on shaft 94 rocked by lever 95 connected by pitman 96 to a crank on the end of a shaft 97. Said pitman is adjustable on the lever to vary the stroke of oscillation according to the rate of feed desired. The last-named shaft is rotated by small ring-gear 98 driven by pinion 99 on another shaft 100, while the latter is driven by pulley 101 on its end over which a belt from the aforementioned pulley 55 on the driving shaft is trained.

60 The operation of the machine will be obvious to those skilled in the art, but a brief description thereof will facilitate understanding and render it entirely clear. Let it be assumed that the material is feeding through the hopper (89) and that a continuous draft of air is generated by the fan (87). The material feeding through the spout of the hopper into the trough space will drop onto the upper raceway of the ring plate under the upper series of balls revolving

5 at high speed. These balls will accordingly crush the material and in so doing distribute it over the raceway surface, carrying the smaller particles therewith against the raceways of the pressure plate, especially if the material is at all moist. As the material is thus distributed and ground under the upper ball series, it sifts down onto and over the extension plate 35 from which it trickles onto the lower series of balls by which it is similarly crushed to a finer degree. Passing from under or around the lower ball series, the ground material drops through the opening (86) into the space beneath. As it thus drops, it is caught by the air blast and carried upwardly behind the trough space 15 through the communicating passages 85, 30' and 79 toward the top of the machine. An eddy of air more or less compressed within these passages forms in the open space above the shell member 78 so that any very coarse particles unsuspended therein will strike against the funnel 77 and drop back into the trough for regrinding. The other particles however will be carried upwardly against the deflector plates 76 and around the neck 75, with the very fine pulverized particles carrying off with the blasted air through the flue-pipe and the coarser particles dropping into the funnel so as to return for further grinding like the very coarse particles dropped directly into the trough. This operation continues, with the very fine particles constantly conveying off to the collecting or storage receptacle and the coarser particles returning for regrinding.

20 In the modification of Fig. 6 where only a single series of balls 102 is shown, the grinding ring need be formed with only one raceway surface and the bottom pressure plate may be omitted. When the latter is omitted as shown, the compressor bolts 40 may be extended through 25 a flange or lugs 103 substituted on the driving head in place of said plate. An apron 104 serves to deflect the ground material discharged into the bottom air blast space. Otherwise, the construction and assembly is essentially the same. 30

35 In the modification of Fig. 7 wherein there are three ball series 102, 36 and 37, a combination of the forms of Figs. 1 and 6 may be employed. In this case there are two grinding rings with separators between, one having a single raceway 50 as in Fig. 6 and the other having double raceways as in Fig. 1. The bolts 40 are then advantageously extended through an extra upper pressure plate (38) and carry two sets of compressor springs (41) working on these plates. Two extension plates 35 also are required, but otherwise the assembly is the same as described with reference to Fig. 1.

40 In the modification of Fig. 8, wherein four series of balls are used, the structure is in effect a mere duplication of that shown in Fig. 1. In this case the bolts 40 are extended through double upper and double lower pressure plates and have two sets of compressor springs working 65 on the upper ones.

45 These modified constructions may be desirable for different installments where varying degrees of pulverization are desired, the crush and grind being of course finer with an increased number 50 of ball series. In all essential respects however, the form and mode of operation are the same as described with reference to the main embodiment.

55 The advantages and desirable improvement 75

features of the machine will be readily appreciated without need for further description.

Having thus described my invention, what I claim as new and desire to secure by Letters 5 Patent of the United States is:

1. In a grinding mill, an annular series of 10 grinding balls, a ring plate having an inclined face on which the balls revolve, an annular plate having a plurality of inclined surfaces at obtuse angular relation bearing upon the balls so as 15 to hold them on the inclined face of the ring plate and revolving the balls when itself rotated, means for rotating the second-named plate, and means holding the same with yielding pressure 20 against the balls.

2. In a pulverizing machine, an annular series 25 of crushing balls, a ring plate having an inclined surface on which the balls are revolved, a concentric plate having double inclined faces at obtuse angular relation in two-point bearing upon the balls opposite said surface of the ring plate for centering and holding the same thereon, means holding the concentric plate in yielding pressure against the balls, and means rotating 30 said concentric plate to frictionally revolve the balls in grinding motion.

3. In a pulverizing machine embodying a plurality of annular series of grinding balls, a grinding plate having a plurality of annular raceways 35 on which the ball series rotate, means holding the ball series under yielding pressure on their respective raceways, means feeding the material to be ground over the ball raceways and a discharge for material ground on the raceways; 40 said grinding plate having an annular series of passages therethrough behind the raceways, means providing a space below the discharge communicating with said passages and into which the discharge opens, means providing a space 45 behind the feeding means also communicating with said passages, and means generating a continuous air blast from the first to the second named space through said passages for carrying off the ground material.

4. In a pulverizing machine, a plurality of annular series of grinding balls at different levels, a grinding plate having annular raceways on which the ball series revolve and a series of 50 passages therethrough behind said surfaces, means holding the ball series to their respective raceways under yielding pressure, means for rotating the balls, means feeding the material over the ball raceway surfaces for grinding under the balls, a gravity discharge for ground material, 55 means providing a space under said discharge communicating with the passages in said grinding plate, means providing a space above the feeding means and also communicating with said passages of the grinding plate, means generating 60 a blast of air to convey the discharge from the first to the second of said spaces through said plate passages, and means for returning the coarser particles of ground material to feed under the balls while allowing the finer particles to 65 pass off to a point of collection.

5. A pulverizing machine comprising in combination, an annular series of grinding balls, a grinding ring having a raceway surface on which the balls revolve and passages outside of said 70 raceway surface, a concentric plate holding the balls on their raceway surface under yielding pressure and revolving the same when itself rotated, means rotating said plate, means feeding the material to be ground under the balls, a 75 gravity discharge for the ground material below

the balls, means providing a space into which said discharge opens, means providing another space communicating with the first-named space through passages in the grinding ring behind the feeding means, means generating a continuous blast of air from the first to the second named spaces, baffles in the second-named space for returning the coarsely ground particles to feed under the balls, and means opening from said second-named space for conveying the finely 10 ground particles with the air away to a point of collection. 5

6. In a pulverizing mill, a plurality of annular superposed series of grinding balls, a non-rotary grinding ring intermediate said series, upper and 15 lower rotating driving rings engaging said series of balls, resilient means interconnected and rotatable with said rotating rings and arranged to yieldably press said grinding balls against said non-rotary ring, means for supplying material to 20 said rows of balls in series, and means to cause air to remove the ground material from said mill. 25

7. In a pulverizing mill, a plurality of annular superposed series of grinding balls, a non-rotary grinding ring intermediate said series, upper and 30 lower rotating driving rings engaging said series of balls, resilient means interconnected and rotatable with said rotating rings and arranged to yieldably press said grinding balls against said non-rotary ring, means for supplying material to 35 said rows of balls in series, and means to cause air to remove the ground material from said mill and return coarse particles from the air to be again ground in said mill. 40

8. A pulverizing mill comprising a grinding 45 ring having an inclined ball-contacting surface, a circular row of grinding balls each having a single point contact with said ring, a second grinding ring having a pair of relatively angularly arranged inclined ball-contacting surfaces 50 each having a single point contact with each of said balls for holding said balls in position between said rings, and means for frictionally moving said balls relative to said rings through one of said rings. 55

9. A pulverizing mill comprising a non-rotary grinding ring having an inclined ball-contacting surface, a circular row of grinding balls each having a single point contact with said non-rotary ring, a rotary grinding ring having a pair of relatively angularly arranged inclined ball-contacting surfaces each having a single point contact with each of said balls for holding said balls in position between said rings, and means for frictionally moving said balls relative to said rings 60 through said rotary ring. 65

10. A pulverizing mill comprising a mill casing enclosing a plurality of vertically spaced horizontally arranged rotary grinding rings, a horizontally arranged non-rotary grinding ring intermediate said rotary rings, a circular row of 65 rolling grinding elements contacting with and positioned between each of said rotary rings and said intermediate ring, means for rotating said rotary rings, means for feeding material to be pulverized directly to the outer side of the uppermost row of grinding elements and directing the material pulverized by said uppermost row of grinding elements to the inner side of the lowermost row of grinding elements, and means for removing pulverized material leaving the outer side of said lowermost row of grinding elements. 70

11. A pulverizing mill comprising a mill casing enclosing a plurality of vertically spaced horizontally arranged rotary grinding rings, a hori- 75

zontally arranged non-rotary grinding ring intermediate said rotary rings, a circular row of rolling grinding elements contacting with and positioned between each of said rotary rings and 5 said intermediate ring, means for rotating said rotary rings, means for feeding material to be pulverized directly to the outer side of the uppermost row of grinding elements and directing the material pulverized by said uppermost row of 10 grinding elements to the inner side of the lowermost row of grinding elements, and an air blast for sweeping up pulverized material leaving the outer side of said lowermost row of grinding elements.

12. A pulverizing mill comprising a mill casing having a material outlet in the upper part thereof and enclosing a plurality of vertically spaced horizontally arranged rotary grinding rings, a horizontally arranged non-rotary grinding ring 0 intermediate said rotary rings, a circular row of rolling grinding elements contacting with and positioned between each of said rotary rings and said intermediate ring, means for rotating said rotary rings, means for feeding material to be pulverized directly to the outer side of the uppermost row of grinding elements and directing the material pulverized by said uppermost row of grinding elements to the inner side of the lowermost row of grinding elements, and means for directing 15 a stream of air past the outer side of said lowermost row of grinding elements to sweep up pulverized material leaving said row and directing the material-laden air outside said rows of grinding elements to the upper part of said mill casing.

13. A pulverizing mill comprising a mill casing enclosing a plurality of spaced grinding rings, a circular row of rolling grinding elements contacting with and positioned between said rings, means for rotating one of said rings, means for feeding material to be pulverized to one side of said row of grinding elements, and downwardly projecting baffle means arranged to restrict the discharge from the opposite side of said row of 5 grinding elements and direct pulverized material leaving said row of grinding elements into the path of an air stream adjacent thereto.

14. A pulverizing mill comprising a mill casing enclosing a plurality of spaced grinding rings, a circular row of rolling grinding elements contacting with and positioned between said rings, means for rotating one of said rings, means for feeding material to be pulverized to the outer side of said row of grinding elements, and an inclined baffle depending from one of said grinding rings and at the inner side of said row of grinding elements for directing pulverized material leaving said row of grinding elements outwardly into the path of an air stream adjacent thereto.

15. A pulverizing mill comprising a mill casing enclosing a plurality of vertically spaced horizontally arranged rotary grinding rings, a horizontally arranged non-rotary grinding ring intermediate said rotary rings, a circular row of rolling grinding elements contacting with and positioned between each of said rotary rings and said intermediate ring, means for rotating said rotary rings, means for feeding material to be pulverized to the outer side of the uppermost row of grinding elements and directing the material pulverized by said uppermost row of grinding elements to the inner side of the lowermost row of grinding elements, baffle means for restricting the flow of material between said rows, and means for removing pulverized material leaving

the outer side of said lowermost row of grinding elements.

16. A pulverizing mill comprising a mill casing enclosing a plurality of vertically spaced horizontally arranged rotary grinding rings, a horizontally arranged non-rotary grinding ring intermediate said rotary rings, a circular row of rolling grinding elements contacting with and positioned between each of said rotary rings and said intermediate ring, means for rotating said 5 rotary rings, means for feeding material to be pulverized to the outer side of the uppermost row of grinding elements and directing the material pulverized by said uppermost row of grinding elements to the inner side of the lowermost row 10 of grinding elements, baffle means for restricting the flow of material between said rows, means for passing an air stream past and sweeping up pulverized material leaving the outer side of said lowermost row of grinding elements, and baffle 15 means for restricting the pulverized material discharge from said lowermost row of grinding elements.

17. A pulverizing mill comprising a mill casing enclosing upper and lower rotary grinding rings, a non-rotary intermediate grinding ring, an upper circular row of rolling grinding elements contacting with and positioned between said upper and intermediate rings, a lower circular row of 20 rolling grinding elements contacting with and positioned between said intermediate and lower rings, means for rotating said upper and lower rings, means for feeding material to be pulverized to the outer side of said upper row of grinding elements and directing the partly pulverized material leaving said upper row to the inner side of said lower row of grinding elements, means mounted on and connecting said upper and lower rings for yieldably pressing said upper and lower 25 rows of grinding elements against said intermediate ring, and means for removing pulverized material leaving the outer side of said lower row of grinding elements.

18. A two-stage pulverizer mill comprising a mill casing enclosing a horizontally arranged 45 rotary top grinding ring, a horizontally arranged non-rotary intermediate grinding ring, a horizontally arranged rotary bottom grinding ring, an upper circular row of grinding balls positioned between and contacting with said top and intermediate rings, a lower circular row of 50 grinding balls positioned between and contacting with said intermediate and bottom rings, resilient means for holding said top and bottom rings in yielding relation with said upper and lower rows 55 of balls respectively and supporting said bottom ring, means for rotating said top and bottom rings relative to said intermediate ring, means for directing material to be pulverized to the outer side of said upper row of balls, and said top and bottom rings being constructed and arranged relative to said intermediate ring and mill casing to cause the material being pulverized to pass inwardly through said upper row of balls and then outwardly through said lower row of 60 balls.

19. A two-stage pulverizer mill comprising a mill casing enclosing a horizontally arranged rotary top grinding ring, a horizontally arranged non-rotary intermediate grinding ring, a horizontally arranged rotary bottom grinding ring, an upper circular row of grinding balls positioned between and contacting with said top and intermediate rings, a lower circular row of 70 grinding balls positioned between and contact- 75

- ing with said intermediate and bottom rings, means for holding said top and bottom rings in yielding relation with said upper and lower rows of balls respectively and supporting said bottom 5 ring including a series of bolts extending through said top and bottom rings and compression springs held by said bolts against one of said last mentioned rings, means for rotating said top and bottom ring relative to said intermediate 10 ring, means for directing material to be pulverized to the outer side of said upper row of balls, and said top and bottom rings being constructed and arranged relative to said intermediate ring and mill casing to cause the material being pulverized to pass inwardly through said upper row 15 of balls and then outwardly through said lower row of balls.
20. A two-stage pulverizer mill comprising a mill casing enclosing a horizontally arranged 20 rotary top grinding ring, a horizontally arranged non-rotary intermediate grinding ring, a horizontally arranged rotary bottom grinding ring, an upper circular row of grinding balls positioned between and contacting with said top 25 and intermediate rings, a lower circular row of grinding balls positioned between and contacting with said intermediate and bottom rings, said upper and lower rows of balls being concentric and the balls of said lower row being of smaller 30 diameter than the balls of said upper row, means for holding said top and bottom rings in yielding relation with said upper and lower rows of balls respectively and supporting said bottom ring including a series of bolts extending through 35 said top and bottom rings and compression springs held by said bolts against one of said last mentioned rings, means at the opposite side of said top and bottom rings from said compression springs for rotating said top and bottom rings 40 relative to said intermediate ring, means for directing material to be pulverized to the outer side of said upper row of balls, and said top and bottom rings being constructed and arranged relative to said intermediate ring and mill casing to 45 cause the material being pulverized to pass inwardly through said upper row of balls and then outwardly through said lower row of balls.
21. A multi-stage pulverizer mill comprising upper and lower rotary grinding rings, a non- 50 rotary grinding ring adjacent said upper and lower rings, an upper circular row of rolling grinding elements positioned between and contacting with said upper and non-rotary rings, a lower circular row of rolling grinding elements 55 positioned between and contacting with said non-rotary and lower rings, and resilient means interconnecting and rotatable with said upper and lower rings and arranged to exert a downward resilient pressure on said upper ring and upper 60 row of grinding elements and an upward re-
- silient pressure on said lower ring and lower row of grinding elements.
22. A multi-stage pulverizer mill comprising upper and lower horizontally arranged rotary grinding rings, a horizontally arranged non-rotary grinding ring intermediate said upper and lower rings, an upper circular row of rolling grinding elements positioned between and contacting with said upper and intermediate rings, a lower circular row of rolling grinding elements 10 positioned between and contacting with said intermediate and lower rings, and resilient means interconnecting and rotatable with said upper and lower rings and arranged to exert a downward resilient pressure on said upper ring and upper row of grinding elements and an upward resilient pressure on said lower ring and lower row of grinding elements.
23. A multi-stage pulverizer mill comprising upper and lower horizontally arranged rotary 2 grinding rings, a horizontally arranged stationary grinding ring intermediate said upper and lower rings, an upper circular row of grinding balls positioned between and contacting with said upper and intermediate rings, a lower circular row 2 of grinding balls positioned between and contacting with said intermediate and lower rings, and resilient means interconnecting and rotatable with said upper and lower rings and arranged to exert a downward resilient pressure on 3 said upper ring and upper row of balls and an upward resilient pressure on said lower ring and lower row of balls and to rotatably support said lower ring and lower row of balls from said intermediate ring.
24. In a planetary ball mill, a closed housing, a vertical shaft rotatably mounted therein, means for rotating said shaft, grinding elements comprising two separate series of balls adapted to travel in two superposed horizontally disposed annular paths, a plurality of grinding rings centered about the shaft between which said balls are confined, said rings including an outer grinding ring fixed within said housing and having two grinding surfaces, one for each series of balls, an upper inner ring arranged to contact with the inner upper surfaces of the upper series of balls, a lower inner ring arranged to contact with the inner lower surfaces of the lower series of balls, means for connecting the upper and lower inner rings for simultaneous rotation and for yieldably urging the upper and lower inner rings toward one another, and connecting means for rotating said inner rings relative to said fixed ring, said connecting means including relatively movable parts whereby the inner rings are permitted limited vertical movement with relation to said shaft.

HARRY RAYMOND COLLINS.
